Primary Examiner — Catherine S Posthauer*Assistant Examiner* — Crystal R Ponce(74) *Attorney, Agent, or Firm* — Dunlap Bennett & Ludwig, PLLC(57) **CLAIM**

The ornamental design for a storage container, as shown and described.

DESCRIPTION

FIG. 1 is a front top right perspective view of the storage container, showing my new design;

FIG. 2 is a rear bottom right perspective view thereof;

FIG. 3 is a front elevation view thereof;

FIG. 4 is a rear elevation view thereof;

FIG. 5 is a right side elevation view thereof, with the left side elevation view being a mirror image thereof;

FIG. 6 is a top plan view thereof; and,

FIG. 7 is a bottom plan view thereof.

The unevenly broken lines represent the boundaries of the

claim and form no part thereof.
